UNITED STATES PATENT OFFICE.

ERNST E. L. MONTELUS, OF NEW YORK, N. Y.

DOOR-LOCK.

1,352,304.

Specification of Letters Patent. Patented Sept. 7, 1920.

Application filed May 6, 1919. Serial No. 295,178.

To all whom it may concern:

Be it known that I, ERNST E. L. MONTELUS, a subject of the King of Sweden, and a resident of the city of New York, 5 borough of Manhattan, in the county and State of New York, have invented a new and Improved Door-Lock, of which the following is a full, clear, and exact description.

This invention relates to a door lock, and 10 pertains more particularly to a lock used in connection with a dumb-waiter shaft.

It is a well-known fact that considerable difficulty has been experienced, particularly in apartment houses and hotels, through the 15 throwing of waste down dumb-waiter shafts.

To eliminate this objection, I have devised a lock adapted for use in connection with the doors of dumb-waiter shafts which will render such doors incapable of being opened 20 unless operated by a person in charge who would be in the basement of the building.

A further object of the invention is to provide means associated with the lock, which would prevent the unlocking of any 25 doors other than those to the rear of which the dumb-waiter is positioned.

It will be understood that by accomplishing these results, the danger incident to health and fire is eliminated from apartment 30 houses in which, as aforesaid, it is quite a common practice to throw waste down dumb-waiter shafts.

Reference is had to the attached sheets of drawings which illustrate one practical embodiment of my invention, and in which—

Figure 1 is a side elevational view of one of the individual door locks;

Fig. 2 is a plan view showing certain parts in section, both Figs. 1 and 2 representing 40 the device in locked position;

Fig. 3 is a view similar to Fig. 1, with the device in unlocked position;

Fig. 4 is an end view of the compound adjusting clamp;

Fig. 5 is a side view of the device illustrated in Fig. 4, and—

Fig. 6 illustrates a dumb-waiter shaft to which individual locks are applied to the several doors, and

Fig. 7 is a detail of certain of the parts.

In these various views, like reference numerals designate similar parts, and the reference numeral 1 indicates the side wall of a dumb-waiter shaft, which is provided with 55 openings normally closed by doors 2. Mov-

able in a vertical plane in the shaft, is the usual dumb-waiter carriage 3, suspended therein by means of a cable, such as 4, passing over drums 5 and thence to a source of power. Each door 2 has applied to its inner face, a keeper 6, formed with the usual conventional inclined face.

Secured to each door jamb is a supporting bracket 7, carrying the casing 8 at its outer end. The casing 8 is open at its ends and 60 has rotatably mounted within it, a compound adjusting clamp including stems 9 integral with the central body portion 10. The front and back plates 11 and 12, respectively, are mounted upon either side of the 65 main body portion 10, and all three of these elements are formed with corresponding grooves so that the device assembled presents channels 13, 14, 15 and 16, whose cross section may be varied by means of a bolt 17 70 extending transversely through the body portion and its front and back plates, and a nut 18 engaging the screw-threads formed upon the bolt. A U-shaped latch 19 has its legs mounted within the compound clamp- 75 ing member, its upper end extending above and normally engaging the keeper 6.

A fork 20 having the outer ends of its prongs bent outwardly as indicated at 21, has the body portion of its prongs extending 80 through the channels 14 and 16 of the compound clamping member, the point of joining of said prongs extending to the rear of the clamping member.

Slidably mounted to one side of the casing 8 and within a separate portion of the same, is an arm 22, which is normally held forwardly by means of a spring 23, extending between the casing 8 and the innermost end of the arm 22. The arm 22 is bent toward 95 the fork 20, as indicated by the reference numeral 24, and extends in front of said fork.

Swingingly mounted upon the end of the arm 22 are a pair of levers 25 normally held 100 in a vertical plane by means of springs 29, which have one of their ends secured to each of the levers 25, their opposite ends being connected to a third outwardly extending lever 26. Pins 27 are associated one with 105 each of the levers 25, and are adapted to be engaged by the sides of the lever 26, when the same is locked either upwardly or downwardly.

Reference being had to Fig. 7 it will be 110

seen that should the lever 26 be locked upwardly or downwardly the pins 27 will be engaged and moved, and consequently result in a swinging of one of the levers 25. Now 5 by virtue of the fact that the lower ends of the levers 25 are provided with interengaging gear teeth 25', a swinging of both levers will result, as has been clearly shown in Fig. 3, for a purpose hereinafter more fully 10 specified.

A buffer wheel 30 is revolubly secured upon the lever 26, by means of an axle 31, and the outer ends of the levers 25 are provided with inwardly-extending guides, such 15 as 32, for a purpose hereinafter specified. A cord, such as 33, extends the entire length 20 of the shaft, and is provided with a support for its upper end, permitting reciprocation of said cord. This reciprocation is provided for by means of a mounting for the end of the cord 32, which may take the form 25 of a plate 34, on the upper surface of which there is mounted a spring 36, whose upper end engages an enlarged portion 35 of the cord, the upper end whereof projects through the plate 34.

The body of the cord 33, as aforesaid, extends throughout the entire length of the shaft, and passes through the guides 32 as 30 clearly shown in Figs. 1, 2 and 3, said cord being provided between each pair of guides 32, with an enlarged portion, which takes the form of a pair of hemispheres 37, clamped together by means of a screw 38.

35 In operation it will now be appreciated that the doors 2 cannot possibly be opened considering that the dumb-waiter is at the lowermost portion of the shaft, but upon the same being elevated to the position indicated 40 in Fig. 6, it will be seen that the buffer wheel 30 will be engaged by the side wall of the dumb-waiter 3, and the levers 25 will be swung inwardly by virtue of this engagement, and, consequently, the cord 33 will also 45 be moved inwardly by reason of the guides 32, to the position indicated in Fig. 3. A pull now upon the cord 33, will serve to move the enlarged portion including the two spheres 37, downwardly, and this enlarged 50 portion of the cord 33 will engage the outer ends 21 of the fork 20 and depress the same. In view of the fact that this fork really includes one arm of the lever pivotally mounted intermediate its extremities, the opposite end which includes the latch 19, will 55 be moved upwardly, also indicated in Fig. 3, and disengage from the keeper 6, making it possible for the door 2 to be swung open and rendering accessible the dumb-waiter 3.

60 It is to be appreciated that the spring 23 for the arm 22 is merely provided in cases where the inward movement of the outer ends of the levers 25 would not prove sufficient to cause positive engagement between 65 the enlarged portions upon the cord 33, with

the prongs of the fork 20, as the buffer wheel 30 would be pressed inwardly and tend to slide the arm 22 in a like direction against the action of the spring 23, if such arm should not be clamped to the casing 8. However, it is to be understood that the inward movement of the outer ends of the levers 25 is normally sufficient to permit of positive engagement of the enlarged portions of the cord 33 with the prongs 21 of the fork 20, 70 and the arm 22 may be so clamped. The prongs 21, it will be noted, are flared outwardly so as to serve as a guide for the cord should the latter become slightly displaced from a position directly in front of the open 80 end of the fork.

To provide further adjustment I have devised a compound clamping member clearly shown in Figs. 4 and 5, which, as it will be seen, allows any adjustment of the 85 distance between the outer ends of the latch 19 and fork 20, and the clamping member.

It will be appreciated that I may vary and modify my structure in any number of ways without departing from the scope of my 90 claims.

I claim—

1. A lock in combination with a door, a keeper secured to the inner face of such door, a latch arm engaging the keeper, a fork 95 connected to such latch and extending in an opposite direction therefrom, such latch and fork being pivotally mounted at their point of connection, and means for engaging the fork for depressing the same, whereby to elevate the latch, said means including a cord, formed with an enlarged portion, adapted to engage the fork upon a pull being exerted upon the cord.

2. A lock in combination with a door, a keeper secured to the inner face of such door, a latch arm engaging the keeper, a fork connected to such latch and extending in an opposite direction therefrom, such latch and fork being pivotally mounted at their point 110 of connection, means for engaging the fork for depressing the same, whereby to elevate the latch, said means including a cord, formed with an enlarged portion, adapted to engage the fork upon a pull being exerted 115 upon the cord, and means for moving the cord toward the fork.

3. A lock in combination with a door, a keeper secured to the inner face of such door, a latch arm engaging the keeper, a fork connected to such latch and extending in an opposite direction therefrom, such latch and fork being pivotally mounted at their point of connection, means for engaging the fork for depressing the same, whereby to elevate the latch, such means including a cord, formed with an enlarged portion, adapted to engage the fork upon a pull being exerted upon the cord, and means normally holding the enlarged portion in a posi- 125 130

tion where the same will be incapable of engaging the fork, but upon an exterior body engaging said means, the same is adapted to be actuated so as to move the 5 cord inwardly, whereby the enlarged portion may engage the fork.

4. A lock in combination with a door, a keeper secured to such door, a pivotally mounted lever, one end of such lever including a latch for such door, the opposite end comprising a fork, and actuating means for depressing the fork, such latch and fork being adjustably secured together.

5. A lock in combination with a door, a

keeper secured to the inner face of such 15 door, a latch and a fork connected together and pivotally mounted at their point of connection, a cord, formed with an enlarged portion, capable of engaging such fork to disengage the latch from the keeper but normally out of engagement with the same, means for moving such cord inwardly, including a pair of levers capable of being rocked inwardly, guides secured to the outer ends of such levers, through which guides 20 the cord passes, and means for rocking such levers.

ERNST E. L. MONTELIUS.
